UNITED STATES PATENT OFFICE

NICHOLAS KOPP, OF PITTSBURGH, PENNSYLVANIA, ASSIGNOR TO KOPP GLASS, INCORPORATED, OF SWISSVALE, PENNSYLVANIA, A CORPORATION OF PENNSYLVANIA

DESIGN FOR A DISPLAY STAND

Application filed October 30, 1929. Serial No. 33,217. Term of patent 7 years.

To all whom it may concern:

Be it known that I, NICHOLAS KOPP, a citizen of the United States, residing at Pittsburgh, in the county of Allegheny, and State of Pennsylvania, have invented a new, original, and ornamental Design for a Display Stand, of which the following is a specification, reference being had to the accompanying drawing, forming part thereof.

In the drawing:

Fig. 1 is a top plan view of a display stand, showing my new design;

Fig. 2, an elevation thereof; and

Fig. 3, a cross section on the line III—III of Fig. 2.

I claim:

The ornamental design for a display stand, as shown.

NICHOLAS KOPP.
